CONCRETE FORM

Lee Y. Davis, Atlanta, Ga.

Application March 30, 1948, Serial No. 17,935

6 Claims. (Cl. 25—131)

1

This invention relates to building forms and adjustable scaffolding for positioning and manipulating the forms in the pouring of structural concrete in erecting building walls and the like.

The object of the present invention is to provide building forms, or concrete mold members, which are adjustably supported so that the forms may be moved upward as a wall is poured, whereby a set of forms may be used repeatedly to obtain a wall of desired height.

Another object of the invention is to provide such structure which may be vibrated as the concrete is poured to eliminate the necessity for tamping to prevent air holes in the finished wall.

A further object is to provide means for producing a hollow wall, or one with air spaces, by the use of cores, the vibrating means acting upon the core members in a manner similar to the main forms.

A still further object of the invention is to provide in a device of this character a form which will give a desired pattern or texture to the finished wall, and, at the same time, be releasable from the wall and adjustable upward as the remainder of the assembly is moved upwardly.

Other objects of the invention will become apparent from the following description of one embodiment of the invention when taken in conjunction with the drawings which accompany and form a part of this specification.

In the drawings:

Figure 1 is a vertical section through a portion of a concrete wall with the forms and adjustable scaffolding of the present invention in place;

Figure 2 is an elevational view of the structure shown in Figure 1, parts being broken away;

Figure 3 is a horizontal section taken on the line 3—3 of Figure 2;

Figure 4 is a perspective view of a portion of a form member and the scaffolding; and

Figure 5 is a detail in section of a core member and a portion of the vibrating mechanism.

The present invention, in general, is concerned with concrete building forms which are adjustably supported upon suitable scaffolding so that they may be moved upward as the pouring of the concrete progresses; the scaffolding carrying means to vibrate the forms to eliminate the necessity for tamping and still produce a finished wall free from air holes. The forms include core members so that a hollow wall construction may be made.

Referring to the drawings, in detail, the in-

2

vention comprises scaffolding 1, mold forms 2, and vibrating mechanism 3.

Scaffolding 1 consists of a plurality of spaced frame members, each of which includes a pair of supporting legs 4 and 5 of channel iron of a length to exceed the height of a normal single story building, leg 4 being the inner member of each pair, and leg 5 the outer member. Each pair of legs is joined at the top by a transverse brace strap 6 which positions the legs in proper spaced relation and completes the formation of the frame member. The individual frame members are tied together to form a unitary structure by means of a pair of longitudinal channels 7 secured to the top corners of each frame.

After the foundation 8 and floor 9 have been poured and are set, the scaffolding is set up with the inner legs 4 resting upon the floor 9, the legs 4 being at a sufficient distance back from the outer edge of the foundation so that the wall to be erected will be positioned midway between the legs 4 and 5. The legs 5 will be outside the foundation in an overhanging position. Extensions 10 are provided for legs 5 so that these legs may be supported from the ground. Extensions 10 are provided with U-shaped loops 11 which serve as clamps and slip over the legs 5. An eccentric lever 12, mounted on a pin 13 carried between the legs of the U-clamp 11 and passing through slots in the sides of the extension, serves to tighten the clamp around leg 5 and draw the leg and the extension tightly together. Extensions 10 are sufficiently long to provide considerable adjustment to take care of varied conditions, and the extension either rests upon the ground, or is driven into the ground to gain a stable support. With the eccentric lever in release position, the legs are adjusted on the extensions until the scaffolding is perfectly plumb so that the concrete forms will have an absolutely vertical movement to insure a plumb wall. This adjustable feature permits perfect aligning and leveling of the scaffolding even when the structure is erected upon a hillside.

Each leg of the scaffold is fitted with two slideable supports 14 and 15, which are actually collars of rectangular shape having square openings to receive the channel iron legs. Set screws 16 and 17 are threaded through the respective supports to bear against the legs to hold the supports in desired positions of adjustment.

Supports 14 and 15 hold the concrete forms 2 in proper position to receive the concrete mix. Each form member comprises a rectangular mold board 18 adapted to stand in a vertical position

with its base resting upon the lower support members 14. The front mold board may have projecting ribs 19 upon its rear face in any desired pattern to give a simulated brick, stone or other finish to the wall. Spacers 20 and 21 extending the full length of the mold members are hinged as at 22 and 23 to the top and bottom of the mold members to project at right angles thereto when in operative position and to be flush with the top and bottom edges of the mold boards. Spacers 21 rest upon supports 14, and spacers 20 upon supports 15. It will be noted that supports 14 are longer than supports 15 to extend beneath the lower edge of the mold to carry the weight of the form so that no great strain is imposed upon the hinged spacers. Spacers 20 are of such width that, when abutting the scaffolding legs, they will position the forms with just the proper spacing between them to form a wall of desired thickness. Spacers 21 are somewhat wider, and provided with square notches 24 spaced along their edges to embrace legs 5 of the scaffold. The notches are deep enough to have their inner edges abut the legs 5, when the mold boards are in parallelism with the legs. Notches 24 will prevent the forms from being displaced longitudinally. Latches 25 and 26 are provided to prevent inward movement of the forms before and during the pouring of the concrete. The latches are pivoted to supports 14 and 15 and their hook ends engage openings 27 and 28 in the spacers 20 and 21.

If it is desired to construct a hollow wall, yokes 29, of sufficient length to extend completely across a frame member of the scaffold, and embrace both legs 4 and 5, are placed in position on the legs at a point above the forms, and held by set screws 30 which bear upon the legs. A beam 31 is placed upon the yokes to support a plurality of core members 32. Beam 31 is at least coextensive with the forms and is positioned upon the centers of the yokes to lie midway between the legs 4 and 5 of the scaffold. This places the beam parallel with the forms and directly over the center of the space between them. Cores 32 are elongated members which are square in cross-section. Each has an eye 33 near its upper end to permit it to be hung from beam 31. The eye is of substantially the same width as the thickness of beam 31, and slightly longer than the vertical depth of the beam to permit the core member slight vertical movement with respect to the beam, while preventing side movement. The core members are threaded onto the beam and positioned at equally spaced points therealong.

In order to eliminate tamping of the concrete to prevent air holes in the finished wall, the vibrating mechanism 3 is provided. This comprises a plurality of horizontal shafts 34, 35, 36, 37, and 38 which are driven from a motor 39. Shafts 34 and 38 are supported in bearing blocks 40 which are slidably mounted on legs 4 and 5 of the frame and held in positions of adjustment by means of set screws 41. Shafts 35, 36, and 37 are journaled in yokes 42 similar to yokes 29 and similarly positioned by set screws 43. A belt 44 from a pulley on the motor shaft passes over a pulley 45 on shaft 37. Shaft 37 carries two additional pulleys 46 and 47. A belt 48 passes over pulley 46 to a pulley 49 on shaft 38 and a belt 50 passes around pulley 47 to a pulley 51 on shaft 36 to drive that shaft. Another pulley, 52, on shaft 36 carries a belt 53 to drive pulley 54 on shaft 35, and a belt 55 over pulley 56, also on shaft 35, drives pulley 57 on shaft 34. Thus all

of the shafts are driven, and rotate in the same direction. Each form member carries a plurality of brackets 58 fastened at spaced points along its side. The brackets extend upward and outward from the forms and terminate in a hook-like end of substantially inverted V-shape. Bearing blocks 40 are so adjusted that shafts 34 and 38 are in contact with the undersides of the inverted V-portions of the brackets. Shafts 34 and 38 are of non-round cross section between bearing points, and the rotation of the shafts will cause impacts to be delivered to the brackets thus vibrating the form. Core members 32 are provided with openings 59 below eyes 33 to accommodate shaft 36. The openings are large enough to permit brackets 58 to be mounted therein, the brackets being attached to the core members and resting upon shaft 36 which is also of non-round cross-section between bearing points. Rotation of shaft 36 will cause vibration of the core members so that the settling action will be uniform both inwardly and outwardly of the poured wall. Motor 37 is mounted upon a platform 61 which is carried by the inner adjustable support 14.

It will be evident from the above that the entire assembly is adjustable so that the forms, vibrating mechanism, etc., may be moved upward as the wall is poured. The front mold member 18, if it is provided with a rib pattern, cannot of course be moved straight up as the wall is built. It must first be moved outwardly to release the ribs from the wall. To accomplish this, the upper forward support 15 must first be moved downward. Hinged spacer 20 may then be swung downward, and spacer 21 may be swung upward after catches 25 and 26 have been released. The form is then free to be moved outwardly to disengage the ribs from the grooves. When the entire assembly has been adjusted upwardly the front form may then be placed in its proper position with the spacers swung to rest upon the supports 14 and 15. Latches 25 and 26 will be fastened and the form will be rigidly held in place.

While in the above there has been disclosed one embodiment of the invention, it will be apparent to one skilled in the art that changes may be made without departing from the scope of the appended claims.

What is claimed is:

1. Concrete forms comprising, a scaffolding including pairs of legs, the pairs being spaced apart longitudinally of the scaffolding, and the legs of a pair being spaced apart transversely of the scaffolding, adjustable supports on said legs, a pair of mold boards adapted to be positioned longitudinal of said scaffolding between the legs of each pair and rest on said supports, spacers hingedly connected to said mold boards to contact said legs when raised to position said mold boards with respect to said scaffolding, and to each other, and said spacers having notches to embrace said legs to prevent longitudinal movement of said mold boards.

2. Concrete forms comprising, a scaffolding including pairs of legs, the pairs being spaced apart longitudinally of the scaffolding and the legs of a pair being spaced apart transversely of the scaffolding, adjustable supports on said legs, a pair of mold boards adapted to be positioned longitudinal of said scaffolding between the legs of each pair and rest on said supports, spacers hingedly connected to said mold boards to contact said legs when raised to position said mold boards with respect to said scaffolding, and to

each other, said spacers having notches to embrace said legs to prevent longitudinal movement of said mold boards, and latch members carried by the adjustable supports to engage said spacers to prevent said mold boards from moving toward or away from each other.

3. Concrete forms comprising, a scaffolding including pairs of legs, the pairs being spaced apart longitudinally of the scaffolding and the legs of a pair being spaced apart transversely of the scaffolding, adjustable supports on said legs, a pair of mold boards adapted to be positioned longitudinal of said scaffolding between the legs of each pair and rest on said supports, spacers hingedly connected to said mold boards to contact said legs when raised to position said mold boards with respect to said scaffolding and to each other, additional adjustable supports on said legs, shafts journaled in said additional supports, said shafts between journal points being non-round in cross-section, brackets attached to the outer sides of said mold boards and having horizontal portion to rest upon the non-round portions of said shafts, and means to rotate said shafts.

4. Concrete forms comprising, a scaffolding including pairs of legs, the pairs being spaced apart longitudinally of the scaffolding and the legs of a pair being spaced apart transversely of the scaffolding, adjustable supports on said legs, a pair of mold boards adapted to be positioned longitudinal of said scaffolding between the legs of each pair and rest on said supports, spacers hingedly connected to said mold boards to contact said legs when raised to position said mold boards with respect to said scaffolding and to each other, yokes bridging each of said pairs of legs and adjustable thereon, a beam to rest upon said yokes, a plurality of core members each having an eye in its upper end whereby said core members may be threaded upon said beam to hang between said mold boards, additional adjustable supports on said legs, shafts journaled in said additional supports, said shafts between journal points being non-round in cross-section, brackets attached to the outer sides of said mold boards and to said core members and having horizontal portions to rest upon the non-round portions of said shafts, and means to rotate said shafts.

5. Concrete forms comprising, a scaffolding including pairs of legs, the pairs being spaced apart longitudinally of the scaffolding and the legs of a pair being spaced apart transversely of the scaffolding, adjustable supports on said legs, a pair

of mold boards adapted to be positioned longitudinal of said scaffolding between the legs of each pair and rest on said supports, spacers hingedly connected to said mold boards to contact said legs when raised to position said mold boards with respect to said scaffolding and to each other, said spacers having notches to embrace said legs to prevent longitudinal movement of said mold boards, latch members carried by the adjustable supports to engage said spacers to prevent said mold boards from moving toward or away from each other, yokes bridging each of said pairs of legs and adjustable thereon, a beam to rest upon said yokes, a plurality of core members each having an eye in its upper end whereby said core members may be threaded upon said beam to hang between said mold boards, additional adjustable supports on said legs, shafts journaled in said additional supports, said shafts between journal points being non-round in cross-section, brackets attached to the outer sides of said mold boards and to said core members and having horizontal portions to rest upon the non-round portions of said shafts, and means to rotate said shafts.

6. Concrete forms comprising, a scaffolding including pairs of legs, the pairs being spaced apart longitudinally of the scaffolding and the legs of a pair being spaced apart transversely of the scaffolding, adjustable supports on said legs, a pair of mold boards adapted to be positioned longitudinal of said scaffolding between the legs of each pair and rest on said supports, spacers hingedly connected to said mold boards to contact said legs when raised to position said mold boards with respect to said scaffolding and to each other, at least the outer legs of said pairs having telescoping sections whereby the scaffolding may be plumbed, and clamps for holding said telescoping sections in positions of adjustment.
